SMOOTHING APPARATUS

David A. Wallace, Detroit, Mich., assignor to
 Chrysler Corporation, Highland Park, Mich., a
 corporation of Delaware

Application February 4, 1944, Serial No. 521,061

3 Claims. (Cl. 51—131)

This application relates to a smoothing apparatus. More specifically it relates to an apparatus for polishing a concave surface such as that of a reflector.

An object of the present invention is to provide an improved smoothing apparatus involving a rotating work holder and rotating smoothing means.

Another object is the provision of improvements in an apparatus for smoothing a concave surface of an article.

A further object is to improve an apparatus for providing a polished concave surface on an article, involving a driven article holder, driven polishing elements, and control of the relative speeds of the holder and polishing elements and shifting of the polishing elements across the holder.

One of the main objects of the invention is the provision in apparatus of this kind of mechanism for producing relative movement between a concave work surface and a freely rotatable abrading element which is the resultant of rotative movement of the work and revolving of the abrading element about angularly related axes and of an additional component movement of the abrading element about its rotative axis resulting from the action of the first two mentioned component movements while the abrading element and work are engaged together.

An additional object of the invention is to provide apparatus of this kind which is adapted to urge the abrading elements against the work surface with uniform and relatively light pressure of such value as to accommodate angular adjustment of the abrading elements with respect to portions of the work of diverse curvatures without scratching or otherwise injuring the work surface.

Other objects of the invention are to provide freely rotatable and angularly variable abrading elements in apparatus of this character which are adapted to become self-adjusted to portions of a concaved surface of varying curvatures to provide means for drivingly producing a relative revolving movement between a work surface and freely rotatable abrading elements which, when the work and elements are engaged, causes a simultaneous rotative movement of the latter; to provide means for drivingly rotating the work in a selected direction with respect to abrading elements during rotation and revolution thereof in the foregoing manner, and to provide apparatus of this kind in which the rotation of the work alone can be relied upon to produce corre-

sponding rotative and revolving movements of the abrading element through contact of the latter with the work.

Other objects will appear from the disclosure.

5 In the drawings,

Fig. 1 is a front view of the novel apparatus of the present invention;

Fig. 2 is a side view of the same apparatus;

Fig. 3 is an enlarged vertical sectional view taken through the apparatus, and

Fig. 4 is a sectional view taken on the line 4—4 of Fig. 3.

The reference character 10 designates a supporting framework, upon the top of which is 15 mounted by means of bearings 11 and 12, a rockable member 13. The rockable member 13 carries integral bracket portions 14 to which is affixed a stand 15 for an electric motor 16. One end of the rockable member 13 carries a clamping part 17 integral therewith to which is pivotally connected a mating clamping part 18. The clamping parts are held together by a swing bolt 19 and a wing nut 20 threaded thereon. Clamping parts 17 and 18 hold a bearing 21 in which is 25 mounted sleeve 22. The lengthwise position of the bearing 21 upon the sleeve 22 is fixed by set collars 23. The sleeve 22 has a lower enlarged end 24 in which are threaded three pins 25. A rod 26 is slidably and rotatably mounted within 30 the sleeve 22 and has adjacent its upper end a shoulder 27 against which rest weights 28. The weights 28 have central openings through which the portion of the rod 26 beyond the shoulder 27 extends. The rod 26 has a spherical lower end 29 retained in a block 30 by means of a perforated plate 31 attached to the block 30 by screws 32. The block 30 is the central portion of a framework 33 which also includes three outwardly extending arms 34. Upon each arm 34 is adjustably mounted a member 35 which may be fixed 40 to the arm 34 by means of a set screw 36. Each member 35 has a lower pointed end 37 fitting into a recess 38 in a backing 39 forming part of a polishing element 40. Polishing element 40 also 45 includes a plurality of segments 41 formed of polishing material and arranged annularly. There are three polishing elements 40, one associated with each arm 34. A pulley 42 is secured to the upper end of the sleeve 22 by a set screw 50 43. The pulley 42 is connected with a pulley 44 by a belt 45. The pulley 44 is carried and driven by the motor 16, which also supports a housing 46 having gearing, not shown, therein for drivingly connecting the pulley and the shaft of the motor.

Positioned within the lower part of the framework 10 is an electric motor 47 which carries at one end a housing 48 for gearing, not shown, which connects the motor 47 with a pulley 49. The pulley 49 is connected by a belt 50 with a pulley 51 secured to a vertical shaft 52. The lower end of the shaft 52 is supported by a bearing 53. The upper part of the vertical shaft 52 carries an article holder 54 upon which is positioned an article such as a reflector 55 having a concave inner surface 56 to be polished, which may be of parabolic form. The reflector 55 is retained in the holder 54 by means of cleats 57 extending slightly inwardly from the upper edges of the holder 54. The holder 54 carries at its under side a thrust collar 58 secured thereto by bolts 59. The thrust collar 58 has a projecting portion 60 which rests against a projecting portion 61 of a stationary thrust collar 62 secured by bolts 63 to a block 64 mounted upon an intermediate portion of the framework 10.

As is evident from Fig. 1, the sleeve 22 and the rod 26 are slightly inclined to the vertical and this inclination is determined and maintained by means of an arm 65 secured to the rockable member 13, a threaded rod 66 pivoted at 67 in a bracket 68 secured to the upper part of the framework 10, and a nut 69 connected to the arm 65 and having threaded engagement with the threaded rod 66. Fingers 70 projecting from the nut 69 facilitate adjustment of the nut along the threaded rod 66 and in this way the rockable member 13 is rocked and the angle of the sleeve 22 and the rod 26 to the vertical is adjusted.

In operation the polishing elements 40 are in engagement with the concave surface 56 of the reflector 55 as shown in Fig. 3. The reflector 55 is rotated by the motor 47 acting through the pulleys 49 and 51, shaft 52, and the holder 54. The polishing elements 40 are revolved about the axis of the sleeve 22 and each element is rotated about an axis extending along the rod 26, this axis falling within the polishing elements and being inclined to the axis of rotation of the holder 54 and the reflector 55. The direction of rotation of the polishing elements 40 is opposite to the direction of rotation of the reflector 55 and the speed of rotation of the polishing elements 40 is preferably less than that of the reflector 55 and indivisible in it. With the sleeve 22 at an angle to the vertical, as shown in Fig. 1, the polishing elements 40 will cover a portion of the reflector 55 from adjacent the center thereof to near the outer edge. Since the directions of rotation are opposite to one another, the relative speed of the polishing elements with respect to the reflector will be high at the outer edge of the reflector, the polishing elements moving in one direction at this region and the reflector in the opposite direction, and the relative speed of the polishing element with respect to the reflector will be low at a region near the center of the reflector, the polishing elements and the reflector moving in the same direction at this region. The polishing action is, of course, greater with greater relative speed between reflector and polishing element. This arrangement is of advantage, for by virtue thereof the greater polishing or smoothing action takes place near the outer edge where a given area is passed over by a polishing element a relatively small number of times, and the lesser polishing action will take place adjacent the center where a given area is passed over by a polishing element a relatively great number of times. The

speed of the reflector 55 may be 60 R. P. M. for example, and the speed of the polishing elements 40 may be 18 R. P. M. It is to be seen that 18 is not divisible into 60 and therefore, the polishing elements will not immediately pass over the same regions of the reflector 55 in such a way as to form grooves at the parts passed over. Appropriate pressure of the polishing elements 40 against the reflector 55 is applied through the weights 28 acting against the upper end of the rod 26. The pointed end 37 on the member 35 carried on the arms 34 and the recesses 38 and the polishing elements 40 allow the appropriate tilting of the polishing elements in conformance with the concave surface 56 of the reflector 55 and yet insure the rotation of these polishing elements. The polishing elements 40 are driven by the motor 16 acting through the pulleys 44 and 42, the sleeve 22, and the pins 25, the latter engaging the arms 34. The connection of the framework 33 to the rod 26 in the spherical end 29 on the rod 26 and the block 30 of the framework 33 provides a universal joint between these parts so that the framework 33 may tilt appropriately. Three polishing elements 40 are provided, for this number assures a proper contact with the surface to be polished. The spacing of one member 35 from the rod 26 may vary from the spacing of the other two members 35 in order uniformly to apply the polishing action to the entire surface of the work, so that the one polishing element 40 does not overlap the other two or overlap them to a desired extent. The spacing of each may be different if desired. If the complete area of the concave surface 56 is not covered by one position of the sleeve 22, this sleeve may be adjusted with respect to the vertical to assure the covering of the complete area. As has been stated, the reflector 55 is rotated about its own center and the polishing elements 40 are revolved, i. e., move about an axis spaced from them and coincident with the axis of rotation of the driving sleeve 22. Consequently, the polishing elements rotate about their own axes passing through the pointed ends 37 and the recesses 38. This rotation may vary as the element passes across the surface 56.

The absolute and relative speeds of the article being polished and of the polishing elements may be varied to suit the article and the type of polishing or smoothing desired. The terms "polishing" or "smoothing" have been used throughout the specification, and it is to be understood that they are to cover an action of relative movement between tool and work that may involve either rough or smooth removal of material or the pressing down of the surface of the work.

In an alternative mode of operation only the work is rotated, and there is no positive revolving of the polishing elements, the drag of the work upon the polishing elements causing them to revolve about the sleeve 22 and to rotate about their own axes.

In a further alternative mode of operation the polishing elements may be revolved positively in the same direction as the work. Although this mode may not equalize total polishing action at the center and the edges of the work as will the first described mode of operation, there may be conditions under which this equalizing is not mandatory or other conditions under which an increased polishing action at the edges is desirable.

It will be apparent from the foregoing description that a new and novel polishing apparatus

has been provided which operates by smoothing of the surface to be polished. The apparatus has been illustrated as applied to the polishing of a concave surface. The principles of the apparatus may be applied also to convex and plane surfaces without a departure from the spirit of the invention.

The intention is to limit the invention only within the scope of the appended claims.

I claim:

1. An apparatus for smoothing a curved surface on an article, comprising means for rotating the article, a plurality of spaced smoothing elements, and means for rotating the smoothing elements about an axis spaced from the axis of rotation of the article and between the smoothing elements, said last mentioned means including a driving sleeve, a rod mounted in the sleeve for rotation and axial movement with respect thereto, a framework engaging the smoothing elements to maintain them in spaced relation and to permit tilting of the smoothing elements in conformance with the curvature of the surface being smoothed, means connecting the framework to the rod in a universal joint for applying pressure from the rod to the smoothing elements independently of the sleeve, and driving means on the sleeve engaging the framework to cause the driven sleeve to drive the framework.

2. An apparatus for smoothing a concave surface on an article, comprising means for rotating the article, a plurality of spaced smoothing elements, and means for rotating the smoothing elements about an axis spaced from the axis of rotation of the article and between the smoothing elements in a direction opposite to the direction of rotation of the article, said last mentioned

means comprising a framework having portions projecting into recesses in the smoothing elements for rotating them and permitting them tilting movement while maintaining them in engagement with the surface being smoothed, a driven sleeve having driving engagement with the framework, a rod mounted in the sleeve for rotation and axial movement with respect thereto, means connecting the one end of the rod and the frame-

5 work in a universal joint, and a weight carried on the other end of the rod for acting through the rod and the framework to apply pressure to the smoothing elements.

10 3. An apparatus for smoothing a concave surface on an article comprising means for rotating the article, three spaced smoothing elements, means for rotating the elements in contact with the surface being smoothed about an axis between them and spaced from the axis of rotation of the curved surface in a direction opposite to the direction of rotation of the article, said last mentioned means comprising a framework formed of three arms extending outwardly from a common central region and guiding and maintaining the smoothing elements in contact with the surface being polished, a driven sleeve, three parts projecting from the driven sleeve into engagement with the three arms for rotating the framework, a rod mounted in the sleeve for rotation and axial movement with respect to the sleeve, and means forming a universal connection between one end of the rod and a central region of juncture of the arms of the framework, and means acting directly on the rod and independently of the sleeve to 20 25 30 35 apply pressure to the smoothing elements.

DAVID A. WALLACE.
